(57) **CLAIM**

The ornamental design for a display stand case table, as shown and described.

DESCRIPTION

FIG. 1 is a perspective view of a display stand case table of the present design;

FIG. 2 is a second perspective view of the display stand case table of FIG. 1;

FIG. 3 is a front view of the display stand case table of FIG. 1; FIG. 4 is a rear view of the display stand case table of FIG. 1; FIG. 5 is a first side view of the display stand case table of FIG. 1;

FIG. 6 is a second side view of the display stand case table of FIG. 1;

FIG. 7 is a top view of the display stand case table of FIG. 1; FIG. 8 is a bottom view of the display stand case table of FIG. 1;

FIG. 9 is a perspective view of the display stand case table of FIG. 1 in a table configuration; and,

FIG. 10 is a second perspective view of the display stand case table of FIG. 1 in the table configuration.

The broken-line disclosure is understood to represent portions of the article in which the claimed design is embodied, but which form no part of the claimed design.
